UNITED STATES PATENT OFFICE.

MILLER REESE HUTCHISON, OF WEST ORANGE, NEW JERSEY, ASSIGNOR TO LOVELL-McCONNELL MANUFACTURING COMPANY, A CORPORATION OF DELAWARE.

DIAPHRAGM-HORN.

1,148,687.

Specification of Letters Patent. Patented Aug. 3, 1915.

Application filed May 11, 1911. Serial No. 626,493.

To all whom it may concern:

Be it known that I, MILLER REESE HUTCHISON, a citizen of the United States, and resident of West Orange, in the county of Essex, sex and State of New Jersey, have invented 5 certain new and useful Improvements in Diaphragm-Horns, of which the following is a specification:

This invention relates to alarm or signaling apparatus. Its various embodiments 10 will be useful for many different purposes, but especially for use on vehicles, boats, factories and elsewhere where a powerful sound is desirable.

In numerous prior applications and 15 patents I have disclosed various forms and modes of operation of mechanically-actuated diaphragm horns adapted for such purposes, and have discussed various principles 20 of construction applicable as well in the present case. As illustrative of the broader principles of such signals I have hitherto shown a preferred form of diaphragm which is wholly clamped about its edges.

In accordance with my present invention 25 I generate the sound by means of a diaphragm unclamped and free for more or less bodily movement at one or more of its edges, whereby increased amplitude of vibration is 30 attained, and the flexure, where flexing occurs, may be transverse, rather than circumferential, and in such case the flexure is preferably at right angles to the grain of the metal, wood or other material of the diaphragm.

With this diaphragm I preferably associate 35 a horn or projector, which casts the sound in the desired direction and may also act as an amplifier. I find that by vibrating the diaphragm of such a horn signal at high 40 frequency and through a considerable amplitude by power means acting on the diaphragm through mechanical connections, a sound of large volume, imperative quality and great carrying power may be obtained.

For best results, the horn should be so proportioned that the inclosed air column has a 45 virtual length of half a wave length at the normal operating frequency of the mechanically-actuated, power-driven diaphragm. When this is the case the air column and the diaphragm will vibrate in unison and the output of sound will be maximum. Preferably, the prime mover is an electric motor, and with such a motor, or when other drive is employed permitting, of a degree of 50 55

slip, the signal will be self-governing to hold the diaphragm to a rate of vibration synchronous with the horn or resonator, because the power required of the motor to vibrate the diaphragm at higher frequency 60 will be excessive; the tendency of the diaphragm to vibrate out of unison being strongly opposed by the air column especially when the resonator has a considerable area at the base.

The diaphragm may be either stiff or flexible and elastic, though preferably the latter. In either event, it is preferably so mounted as to be supported at one region, characteristically at one end, and freely displaceable elsewhere. As so constituted, it 65 may be regarded as a freely-movable tongue or reed. Preferably, the partly-free diaphragm is made of spring material, especially sheet spring steel, but other material 70 may be employed. The diaphragm may be either pivotally supported or clamped or otherwise immovably held at one end or edge. In the latter event it performs its vibratory to and fro movement by flexure, 75 establishing a virtual pivot in the vicinity of its clamped portion. In certain instances it is desirable to provide a stationary abutment contacted by the diaphragm in its free movement in the direction away from the 80 actuating means, or the diaphragm may strike against stops in both directions. Such an abutment, particularly when employed in connection with a pivoted, more or less unyielding diaphragm or tongue, may cause the 85 signal to operate with something of a clapper action. Such an abutment used in connection with a resilient diaphragm may cause the diaphragm to produce the alternate waves of compression and rarefaction 90 partly by free movement and partly by central flexure of the diaphragm held between opposed marginal supports. When the diaphragm is pivotally supported and resilient, and when the actuating means is so related 95 thereto as to flex the diaphragm after contacting with the abutment, the abutment enables the diaphragm to execute its return movement by virtue of the elastic stress under which it has been placed. With a diaphragm clamped at one edge so that it is 100 placed under elastic stress by the act of displacement from normal position, the additional stress due to flexure past the stationary abutment, contributes to the vigor of 105

return movement. In other instances the return movements of the diaphragm or tongue may be largely or mainly under the influence of gravity.

5 Various mechanical connections may be employed for enabling the motor or other source of power to vibrate the partly-free diaphragm. I prefer to employ an actuator driven from a power shaft, the actuator being provided with one or more actuating projections, preferably cams, adapted to effect successive displacements of the diaphragm. With such thrust projections the diaphragm is forcibly displaced in one 10 direction by the thrust and returns automatically under elastic stress or the action of gravity, or both, after the passage of the projection or tooth. With such an actuator, the diaphragm may or may not be flung outward clear of the cam tooth, dependent on the formation of the tooth, the speed of rotation, the nature of the diaphragm support, the range of free movement permitted, and the elasticity or rigidity of the diaphragm or tongue. When the abutment is used, the diaphragm may contact therewith either while in the act of being forced by the cam or after being flung clear of the same. In the latter event, the 15 resulting flexure past the abutment, or the more or less rigid impact thereagainst, as the case may be, will take place by virtue of momentum. Obviously, the diaphragm or tongue may be connected with the drive shaft by other means, and either by thrust or tension connections. If desired, the movement of the diaphragm may be forced in both directions.

In the accompanying drawings, illustrating the invention by means of certain of the possible embodiments thereof: Figure 1 is a view partly in section and partly in side elevation of one form of signal; Fig. 2 is a vertical transverse section through a form of inclosing case, taken at the joint between the sections thereof, the unclamped diaphragm and rotary actuator being shown in elevation; Fig. 3 is a front elevation, looking into the mouth of the horn; and Fig. 20 4 is a longitudinal section through the rear part of another form of signal, the parts inside being shown in elevation.

In Figs. 1 to 3, the diaphragm is shown at 10. It is inclosed in a suitable case, an illustrative form of which is shown as comprising the front section 11 and the rear section 12, which may be connected together by screws or bolts 13. The front section 11 is provided with an opening 14 for the escape 15 of sound. Preferably, the diaphragm or tongue is elongated and the opening is elongated in the same direction. Obviously, however, the diaphragm may be of any desired outline.

15 is a horn communicating at its base

with the opening 14, for projecting the sound in a forward direction. As already explained, best results are obtained by so proportioning the horn that it is resonant with the normal operating frequency of the 70 tongue or diaphragm.

The tongue may be of any suitable material, and it may be either stiff or flexible. In the latter instance, it is preferably of spring material, as sheet spring metal. It 75 is preferably supported or clamped at one end or edge, and freely displaceable at all other regions. In the form of the invention shown in Figs. 1 to 3, the diaphragm or tongue is pivotally supported on a pin or 80 shaft 16. Preferably, it is received at its shaft end in a suitable clip or holder 17 journaled on or secured to the shaft.

Suitable power driving means are provided, an electric motor being preferably 85 employed. The armature of such a motor is indicated at 18. Any suitable mechanical connections may be interposed between the motor and diaphragm for vibrating the latter. A simple and preferred embodiment is 90 shown, the same including a disk 19, on the armature or driving shaft 20, and provided with peripheral cam teeth 21. The shaft is received in a suitable bearing sleeve 20^a, which in turn has an external circular bearing in a support 20^b, the shaft and sleeve being eccentric to each other so that rotary adjustment of the sleeve adjusts the cam to or from the diaphragm. The eccentric actuating projections 21 contact with a projection or anvil, such as 22. This may be carried by the diaphragm or by an intermediate part. In the present instance, it is shown as 95 formed with the holder 17. In operation, rotation of the driver 19 successively displaces the diaphragm in one direction. In the particular construction illustrated, the return movements of the diaphragm are free, but it will be obvious that the diaphragm may be so coupled to the driver as 100 to be forcibly displaced in both directions. The free return movement may be performed partly or largely under the influence of gravity. To this end the diaphragm or 105 reed may be pivoted at its upper end, as shown. The thicker and heavier the reed or tongue, the greater will be the effect of gravity in restoring it to normal position.

Preferably an abutment, such as the solid shoulder 23 adjacent the other end of the 110 diaphragm, is provided in position to be contacted by the diaphragm when moving under the impulse imparted by the driver. Such an abutment causes the tongue to operate with something of a clapper or hammer action, and the larger the abutment surface and the heavier and more nearly rigid the tongue, the more pronounced will this clapper action be. With a spring tongue or diaphragm, the abutment may afford a sup- 115 120 125 130

port to coöperate with the pivot or other fixed support, so that the diaphragm is flexed between its ends, either by its own momentum or by the continued forcing by the cam after contact of the diaphragm with the abutment. The energy so stored in the diaphragm enables it to spring back to or past normal position when the actuating projection has ridden off the anvil.

10 Best results are obtained when the outline of the diaphragm or reed and the interior of the case closely conform to each other, so that the diaphragm vibrates with minimum clearance, and therefore with minimum leakage around its edges. The clearance shown in Fig. 2 might be reduced in practice. The space between the diaphragm and the back wall of the case may constitute a resonant space, or another horn

15 may project from this side.

In Fig. 5 I illustrate a form of the invention showing that the diaphragm, here indicated by the character 10^a, may be fixed instead of pivotally supported. In this instance one end is shown clamped between the forward and rearward sections 11^a and 12^a of a suitable case. The diaphragm is preferably of spring material. In the other illustrated form of the invention, the actuating means engaged the tongue or the wear piece secured thereto, at the opposite side of the support from the working area of the tongue.

In the form shown in Fig. 4, the actuating impulses are applied to the body of the diaphragm. For this purpose, a suitable wear piece or anvil 22^a may be riveted or otherwise secured to the working portion of the diaphragm, in position to be engaged by the thrust projections on the driver 19. In this instance, also, the diaphragm preferably

conforms closely to the interior of the case, so that leakage of compression and rarefactions around its edges is minimized.

I claim:

4. In an alarm or signaling device, a horn, a diaphragm unclamped and free for more or less bodily movement at one or more of its edges, a rotary actuator carrying an eccentric projection for engagement with said diaphragm at a point spaced from the free vibrating end and arranged to cause repeated bodily displacements of said diaphragm at high amplitude, velocity and rate, and power means for driving said actuator at a sufficient speed to cause said diaphragm to generate acoustic waves.

5. An alarm or signal, comprising a case, a pivotally supported flexible sound-generating member therein, a horn communicating with the interior of the case, and mechanical means for vibrating said member in the direction of the length of the horn and about its pivotal support comprising a power shaft and connections between said shaft and said member.

6. An alarm or signaling device comprising, in combination, a horn, a vibratory tongue for generating the sound projected by the horn, and mechanical means for actuating the tongue comprising a power-driven rotary member provided with cam projections for displacing the tongue and causing rapid vibrations of a free end portion spaced from said cam projections.

Signed at New York city, in the county of New York, and State of New York, this 9th day of May, A. D. 1911.

MILLER REESE HUTCHISON.
